UNITED STATES PATENT OFFICE.

JOSEPH FRANKLIN SHIPP, OF CHATTANOOGA, TENNESSEE.

DESIGN FOR A BADGE.

SPECIFICATION forming part of Design No. 25,767, dated July 14, 1896.

Application filed October 18, 1895. Serial No. 566,166. Term of patent 7 years.

To all whom it may concern:

Be it known that I, JOSEPH FRANKLIN SHIPP, a citizen of the United States, residing at Chattanooga, in the county of Hamilton 5 and State of Tennessee, have invented and produced a new and original Design for a Button or Badge, of which the following is a specification, reference being had to the accompanying drawing, showing the said design.

10 The leading or characteristic feature of my design consists of a central rectangular panel surrounded by a narrow field upon which may be placed suitable inscriptions, the said central panel being provided with diagonal crossing bars, upon the surface of which bars are

arranged a series of five-pointed stars, the star at the junction of the two series belonging to each of the said series.

A is the central rectangular panel. B is the field for inscriptions; C, the diagonal 20 crossing bars, carrying upon their surface the series of five-pointed stars.

What I claim is—

The design for the button or badge herein shown and described.

JOSEPH FRANKLIN SHIPP.
